[57] CLAIM

The ornamental design for a spinning toy, as shown and described.

DESCRIPTION

FIG. 1 is a top plan view of a spinning toy showing my new design;

FIG. 2 is a front elevational view thereof;

FIG. 3 is a rear elevational view thereof in an inverted position;

FIG. 4 is a bottom plan view thereof;

FIG. 5 is a elevational view thereof taken at 90° with respect to FIG. 2; and

FIG. 6 is an elevational view of the side opposite that shown in FIG. 5 in an inverted position.
